MEDICINE FEEDING DEVICE

Julia Dorozinski, New York, N. Y.

Application April 27, 1939, Serial No. 270,301

1 Claim. (Cl. 30—141)

The present invention is generally concerned with medicine applicators and is more particularly directed to medicine feeding devices. The dominant object of the invention is realized in the provision of a simplified but functionally and structurally improved medicine feeding device comprising a dished receptacle for initially storing liquid medicine and including a posterior but relatively elongated channeled and attenuated trough or chute for directing the flow of medicine from the receptacle or bowl directly to the esophagus of the user and thereby precluding the medicine from coming into contact with the taste glands of the mouth. As a further object the invention comprehends the provision of a serviceable medicine feeding device having means to guard the flow of medicine to prevent such flow from reaching the teeth of the mouth. The invention has as a further and important object the provision of novel medicine feeding means adapted in part to be lightly sustained by the dorsal part of the tongue of the mouth and having means to directly guard the flow of medicine to the esophagus.

With the above and other important objects, advantages, features, and aspects in view and readily apparent from the teachings of the present disclosure, the invention further resides in the details of construction and arrangement of parts hereinafter more specifically pointed out in the following detailed description considered in connection with the accompanying drawing wherein:

Fig. 1 is a perspective view of the medicine feeding device according to my invention and showing the posterior and arcuate portion thereof lightly seated on the dorsal part of the tongue of the user and guarding the flow of medicine directly from the communicating basin or bowl to the esophagus.

Fig. 2 is a plan view of the medicine feeding device shown in Fig. 1.

Fig. 3 is a side elevational view of the medicine feeding device, and

Fig. 4 is a sectional view on the line 4—4 of Fig. 2.

Illustrative of the embodiment disclosed, the medicine feeding device is generally denoted 10 and comprises a one piece member having an anterior medicine liquid receptacle in the form of a concavo-convex bowl or dish 11 and a posterior or rearwardly extending liquid carrier guard broadly denoted 12 which is integral with the body of the bowl.

As illustrated the guard comprises a longitudi-

nally disposed channel or chute 13 communicating directly with the basin or chamber of the receptacle 11 and is co-extensive with the length of the body of the attenuated guard. This guard has an arcuate contour and terminates in the laterally extending curved lips 14 forming a part of the laterally extending and curved and inclined flanges 15 which are integral with the body of the medicine receiving bowl 11.

As a commentary in respect to the utilization 10 of the present feeding device according to the invention the bowl is first supplied with a charge of liquid medicine and the posterior upwardly and downwardly curved guard 12 is located lightly on the tongue and shifted to position lips 14 adjacent the entrance of the esophagus.

It will be observed that although the downwardly curving reduced or attenuated guard is seated lightly on the dorsal part of the tongue, the laterally extending and inclined flanges 15 20 constitute means to prevent slippage of the liquid medicine out of the trough at a time when the bowl is slightly tilted upwardly for automatically directing the flow of the medicine into the channel 13 of the trough or guard 12 and from 25 the latter directly into the esophagus. Hence it will be appreciated that with the novel feeding device in accordance with the present invention, medicine may be directly fed into the esophagus without however coming into intimate contact 30 with the taste buds or glands of the mouth and concomitantly precluding injury to the enamel structure of the teeth by reason of any chemical action of the medicine in that the medicine is continuously confined during its passage of flow 35 in the trough or depressed means 12 as is well understood from the teachings of the present disclosure. The herein disclosed feeding device may be of any suitable material, for example; relatively heavy paper, relatively thin cardboard, or 40 of an appropriate metal and for purposes of specification, the part of the trough 12 adjacent the bowl may be considered as expanded or flared while the terminal part of the trough may be considered as reduced or restricted although the 45 channeled portion of the guard may be considered as beaded means serving also to reinforce the body of the guard.

While the invention has been specifically described in detail, it is to be understood that it 50 is not limited to specific details herein described but is capable of other adaptations and modifications within the scope of the appended claim.

I claim:

In a medicine feeding device, a one piece mem- 55

ber comprising an elongated body having an anterior bowl shaped portion and a posterior arcuate guard integral with said portion and provided with laterally extending and inclined flanges and including a longitudinally and medially arranged channel communicating with said bowl and substantially coextensive with the length of said

guard, said guard comprising an expanded portion adjacent said bowl shaped portion and including a downwardly and rearwardly curved terminal restricted portion provided with arcuate lips contiguous to the posterior terminal portion of said guard.

JULIA DOROZINSKI.
